Specification for Design.

Patented Nov. 8, 1921.

Application filed March 7, 1921. Serial No. 450,490. Term of patent 3½ years.

To all whom it may concern:

Be it known that I, FRANK BISSONETTE, a citizen of the United States, residing at Winooski, in the county of Chittenden and State of Vermont, have invented a new, original, and ornamental Design for a Shrine, of which the following is a specification, reference being had to the accompanying drawing, forming a part thereof.

The figure is a plan view of the shrine, showing my new design.

I claim:

The ornamental design for a shrine, as shown.

FRANK BISSONETTE.
